Primary Examiner — Eric Goodman*(74) Attorney, Agent, or Firm* — Davis Wright Tremaine LLP; George C. Rondeau, Jr.(57) **CLAIM**

The ornamental design for an equipment rack panel, as shown and described.

DESCRIPTION

FIG. 1 is a top front perspective view showing our new design.

FIG. 2 is a front elevational view thereof.

FIG. 3 is a rear elevational view thereof.

FIG. 4 is a left side elevational view thereof.

FIG. 5 is a right side elevational view thereof; and,

FIG. 6 is a top plan view thereof, the bottom plan view being a mirror image.

The broken lines are for illustrative purposes only and form no part of the claimed design.
